(57) **CLAIM**

The ornamental design for an angled XLR connector as shown and described.

DESCRIPTION

FIG. 1 is a perspective view showing the new, original, and ornamental design of an angled XLR connector;

FIG. 2 is a perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top side plan view thereof; and,

FIG. 8 is a bottom side plan view thereof.

The broken lines shown in the drawings depict portions of the angled XLR connector that form no part of the claimed design.
